UNITED STATES PATENT OFFICE.

BUDOLF SCHÜRMANN, OF BERLIN, GERMANY, ASSIGNOR TO TAXAMETER AKTIEN-
GESELLSCHAFT, OF BERLIN, GERMANY.

REGISTERING APPARATUS FOR TAXIMETERS AND THE LIKE.

1,120,749

Specification of Letters Patent. Patented Dec. 15, 1914.

Application filed April 10, 1913. Serial No. 760,199.

To all whom it may concern:

Be it known that I, RUDOLF SCHÜRMANN, a citizen of the German Empire, residing at Berlin, in the Kingdom of Prussia, German Empire, have invented new and useful Improvements in Registering Apparatus for Taximeters and the like, of which the following is a specification.

This invention relates to registering apparatus of the type in which lines are traced automatically by a pencil on a record sheet. These lines serve to register certain movements or sequences of events and their dependence on other movements or events. As an example, an apparatus of this type designed for a taximeter should indicate by means of the record lines what are the tariffs at which the taximeter was working, what distances were traveled while the respective tariffs were in operation, the times at which the taximeter was put into operation and when the separate distances traveled were completed. The times at which the respective events are recorded, (the settings to different tariffs, and the respective distances traveled,) are indicated because the paper strip or disk on which the record is made, is moved forward uniformly and continuously, so that each instant of time corresponds to a certain section of the record. The movements of the pencil corresponding to the different operations to be recorded are made at right angles to the direction of movement of the paper. If different events are to be recorded, (e. g. in the above example, the different tariff settings of the instrument and also the distances traveled,) the movement of the pencil must be effected by various operating mechanisms. In addition to these possibilities of movement of the pencil which necessitate already quite complicated mechanism, two further movements of the pencil have to be provided for in the usual constructions. In the first place the pencil must be able to move vertically to and from the paper surface against which it must be pressed with a light spring pressure, so that the line is drawn with a uniform pressure of the pencil and so that the pencil is fed up automatically as it wears away. Secondly, the pencil must be capable of being moved by hand completely to one side, for instance when the paper strip or disk is to be changed, and this has to be done daily with

many types of registering apparatus. 55 Further, if the pencil is not pushed to one side, the record cannot be read just at the place where the pencil is resting.

Now this invention consists in mounting the pencil carrier on the cover which serves 60 to close the casing and is hinged thereto, in such a way that when the cover is closed engagement takes place with the operating mechanism by which the pencil is moved corresponding to the events to be registered, 65 and the pencil is raised off the paper surface and pressed to one side when the case is opened, so that neither the reading of the records nor the removal of the record paper are hindered in any way. 70

One form of construction of the invention is shown in Figures 1 to 5, and an alternative form is given in Figs. 6 to 11 of the accompanying drawings:—Fig. 1 shows a registering apparatus for a taximeter with its 75 door open; Fig. 2 is a cross section on the line A—B of Fig. 1 with the door open; while Fig. 3 is the same cross section with the door closed; Fig. 4 is a cross section on the line A—C of Fig. 1; Fig. 5 is a side view 80 of the pencil carrier; Fig. 6 shows another form of registering apparatus for a taximeter, with its door open; Fig. 7 is a cross section on the line A—B of Fig. 6 with the door open, while Fig. 8 is the same cross section with the door closed, showing the connection with the vehicle; Fig. 9 is a cross section on the line A—C of Fig. 6; Fig. 10 is a side view of the pencil carrier; and Fig. 11 shows the cam which serves for moving 90 the pencil carrier.

In both forms of apparatus *a* is one wall of the taximeter apparatus, to which the case *b* of the registering apparatus is fastened. 95

*b*¹ is the cover of the case which is attached to the latter by means of the hinge *c*, and is held closed by means of the staple *d*¹ and clasp *d*² which can be made secure against opening by a lead seal or a padlock, so that the registering apparatus and the record card are only accessible to authorized persons, e. g. the cab proprietor. A shaft *e* driven by clockwork projects through the wall of the taximeter apparatus 100 and through the back of the case *b* into the latter. This shaft carries a pinion *f* which drives a toothed wheel *g* causing it to ro-

tate once in 24 hours. A circular disk of paper *h* can be placed on the nave of the toothed wheel *g* and held in place by the nut *i*. The paper disk is divided into 24 hour divisions and into a number of annular strips corresponding with the number of tariffs or the like to be recorded. The pencil is moved into position over one or other of the annular spaces by setting the taximeter to one or other of the tariffs, when the pencil makes to and fro movements within the width of the strip over a length corresponding to the distance traveled.

In the form of construction shown in Figs. 1 to 5, the actuating of the pencil is not effected directly, but it is done with the help of an additional lever *k* attached to a shaft *l*. The shaft *l* passes through corresponding openings in the case *b* and the taximeter wall *a*, into the interior of the taximeter and is moved to the correct position by one or other of several independent mechanisms (not shown) corresponding with the various tariffs, to one of which the instrument is set, and it is also caused to move to and fro continuously during the running of the vehicle at a rate which increases and decreases with, and corresponds to, the rate at which the vehicle is moving, so as to cover a stretch corresponding with the distance traveled. The to and fro movement of the shaft *l* is caused by a cam or other suitable mechanism operated by the vehicle wheels. In Fig. 8, the shaft *l* is shown as connected to the flexible shaft *5* operated by the lever *4* which is vibrated by the cam *2* carried by or concentric with the vehicle wheel, a spring *6* holding the lever in contact with the cam. The pencil carrier *m* is mounted to turn on the cover *b*¹ of the case. A spring *n* tends to press the pencil carrier against the end of a pin *o*. The pencil *p* is slidably mounted in the carrier *m* and is pressed by a spring *q* against the paper sheet *h* when the cover is closed. The projection *r* serves as a support or table for the paper disk where the pencil works over it. When the lid *b*¹ is shut (see Fig. 3), the pin *m*¹ attached to the pencil carrier *m* presses against a nose *k*¹ on the lever *k*. The pencil carrier *m* is thus caused to be pressed aside against the action of the spring *n*, and the pencil *p* is automatically brought over the correct part of the record disk. The pencil now follows the movements of the lever *k*. When the lid is closed the pencil *p* makes circular movements (which correspond to the divisions for the intervals of time on the paper disk) independently of whether the movements of the lever *k* corresponding to the various performances to be recorded are partly straight line movements and partly turning movements about another axis. The time of recording of each point on the record lines

traced out can thus be ascertained accurately and without risk of error, by its position in its annular strip.

When the case is open the face of the paper disk *h* is entirely exposed. Hence the lines drawn are completely visible to their ends, and the record disk can be easily changed.

The form of apparatus shown in Figs. 6 to 11 differs from that described above in 75 that not only the pencil carrier, but also a part of the mechanism which directly operates the pencil carrier is carried by the cover, and that when the cover of the casing is closed, these parts are brought into 80 engagement by suitable means with the parts which actuate them and which are located in the casing. This arrangement has the advantage that the adjustment of the movements of the pencil can be carried 85 out more easily.

The pencil carrier *m* is pivotally mounted on the lid *b*¹ of the case. A spring *n* tends to turn the pencil carrier *m* until its arm *m*¹ comes against a cam *v*. The cam *v* 90 is fixed on a shaft *u* revolvably mounted on the lid of the case, on the other end of which shaft a bevel wheel *t* is fixed. This bevel wheel engages, when the lid is closed, with another bevel wheel *s* arranged in the 95 casing, and whose turning movements correspond with the records to be made. The pencil *p* is slidably mounted in the pencil carrier *m* and is pressed toward the paper by a spring *q* when the cover is closed. A 100 projection *r* serves as a support or table for the paper disk *h*. When the cover *b*¹ is closed (see Fig. 8) the bevel wheel *t* comes into engagement with the bevel wheel *s*. The pencil carrier with the pencil *p* is now 105 moved to and fro by the cam *v* in a manner corresponding to the movements of the bevel wheel *s*.

In the form of apparatus illustrated it is assumed that when the tariff of the taximeter is changed from one rate to another, the bevel wheel *s* is turned by a single movement through a comparatively large angle, after which it is moved periodically to and fro through a smaller angle at a rate which 115 corresponds to, and increases and decreases with, the rate at which the vehicle is moving so as to make a record corresponding with the distance covered. Consequently a line will be traced by the pencil *p* on the paper 120 disk *h* as indicated in Fig. 6, and this line serves to show at what times the taximeter was moved into its different tariff positions, and also what distances were covered at the various settings and at the respective times. 125 Thus on the disk shown in Fig. 6, the different concentric rings represent the different tariffs and the change in tariff is indicated by the change in position of the line from one to another of these rings, the time 130

of change being thus indicated on the disk as well as the tariff to and from which the change is made. Also on this disk the distance traveled is indicated by the number of 5 transverse to and fro vibrations in the line within the particular ring corresponding to the particular tariff at which the vehicle is being operated. As the rate of movement of the vehicle increases or decreases, the number 10 of these to and fro vibrations also increases and decreases, and to a corresponding extent, so that these vibrations indicate accurately the distance traveled, their frequency thus corresponding with the rate of 15 movement of the vehicle. It will thus be seen that the rotary movement of the paper disk is continuous, and that the line on the disk will indicate the particular time at which any change of tariff is made as well 20 as the period of time at which the vehicle is maintained at each tariff. It will also be seen that when the vehicle is at rest, the line will be a smooth circular arc, and that when 25 the vehicle is in motion the line will consist of a series of to and fro vibrations, whose number will correspond to the distance traveled within the time interval indicated.

When the case is open the paper disk is entirely exposed. The line traced is therefore completely visible to its end, and the record disk can be easily changed, as in the first described construction.

I claim herein as my invention:

1. In a registering apparatus for vehicles 30 the combination with a casing containing a rotatable record member and a removable cover thereon of a recording member mounted on said cover and located in its recording 35 position relatively to the record member when the said cover is in its closed position and leaving the record member unobstructed 40

when the cover is open, a shaft extending into the casing and adapted to be shifted to and fro to correspond with the rate of movement of the vehicle, a driving member 45 on the said shaft, a connecting member mounted on the said cover shifted by the said shaft when the said cover is in its closed position, said driving and connecting members being out of engagement when the 50 cover is open, and means to impart the said shifting movement of the said connecting member to the said recording member.

2. In a registering apparatus for vehicles the combination with a casing and a removable cover thereon of a record member mounted within said casing, a recording member mounted on said cover and located in its recording position relatively to the record member when the said cover is in its 55 closed position and leaving the record member unobstructed when the cover is open, a shaft extending into the casing and adapted to be shifted to and fro to correspond with the rate of movement of the vehicle, a 60 bevel gear on the said shaft, another bevel gear mounted on the said cover adapted to engage the said first bevel gear on the said shaft when the said cover is closed and to be moved out of engagement when the cover is 65 open, a cam adapted to be shifted by the said second bevel gear, a two armed lever one arm of which carries the said recording member while the other touches the said cam, and a spring forcing the said arm 70 against the said cam.

In witness whereof I have hereunto set my hand in presence of two witnesses.

RUDOLF SCHÜRZMANN.
